UNITED STATES PATENT OFFICE.

ANDREW EMIL BARK, OF KALISPELL, MONTANA, ASSIGNOR OF ONE-HALF
TO ROBERT NORDTOME, OF SAME PLACE.

STRINGED MUSICAL INSTRUMENT.

SPECIFICATION forming part of Letters Patent No. 643,452, dated February 13, 1900.

Application filed February 28, 1899. Serial No. 707,167. (No model.)

To all whom it may concern:

Be it known that I, ANDREW EMIL BARK, of Kalispell, in the county of Flathead and State of Montana, have invented a new and Improved Stringed Musical Instrument, of which the following is a full, clear, and exact description.

The object of the invention is to provide certain new and useful improvements in stringed musical instruments, such as citherns or the like, whereby the pitch of all the strings in a group of strings or only a few thereof can be readily raised or lowered, according to the music to be executed.

The invention consists of novel features and parts and combinations of the same, as will be fully described hereinafter and then pointed out in the claims.

A practical embodiment of my invention is represented in the accompanying drawings, forming a part of this specification, in which similar characters of reference indicate corresponding parts in all the views.

Figure 1 is a plan view of the improvement. Fig. 2 is a sectional side elevation of the same on the line 2 2 in Fig. 1. Fig. 3 is an enlarged fragmental perspective view of part of the improvement, and Fig. 4 is a like view of the same with parts in a different position.

The improved stringed musical instrument is provided with a suitable body A, carrying a sounding-board B, having transversely-extending bridges D D', over which is stretched the group of melody-strings E and the group of accompaniment-strings F F' F² F³. The strings are secured at their ends to the fixed pegs G and the tuning-pegs G'. Adjacent to the bridge D are arranged spaced transversely-extending bearings H H', held on the sounding-board B, and a similar bearing H² is arranged on a sounding-bridge adjacent to the bridge D'.

In the bearing H, which is preferably formed on top with a semicircular groove, are mounted to turn the auxiliary bridges I, one for each group of strings E F F' F² F³. Each bridge I is made in the form of a half-round bar, the flat surface of which is normally on top, the ends I' being rounded, so as to be engaged by bearings J in the form of springs secured to the bridge D. One end of each bridge

I is provided with a handle I², extending with its forward end above the plane of the strings; so as to be within convenient reach of the operator, the handles when in a normal downward position holding the flat surfaces of the bridge-bars on the top; but when the handles are thrown upward into a vertical position, as shown in Fig. 4, then the said bridge-bars are turned in the bearing H to engage the under side of the corresponding group of strings and raise the pitch thereof one-half note. The several bridge-bars I abut against one another, the outermost bridge-bars abutting against brackets H³ on the bearing H.

In the bearing H' are arranged similar movable auxiliary bridges K, made of half-round bars, the ends K' being round and engaged by bearings J' and each bar having an arm K² under the control of the operator. When a bridge-arm K² is swung upward, the bridge K engages the strings of the corresponding group and raises the pitch thereof a half-tone over that previously given by the preceding bridge I or one full tone from the bridge D.

In the bearing H² are held movable auxiliary bridges L in the shape of round bars formed with notches L' for some of the strings in the group, each bar being provided at its end with a handle L², normally standing in a horizontal position, the notches L' being turned to one side, so that all the strings in the group rest on the bridge. When the handle L² of a bridge is swung into a vertical position, then the notches L' of this bridge come on top to release the corresponding strings in the group from the bridge, so that the string vibrates from the adjacent fixed bridge D'. The bridges L are so located relatively to the bridge D' that the pitch is raised one-half tone; but when the corresponding arm L² is swung into a vertical position then the pitch of the strings passing into the notches L' is lowered one-half tone.

By the arrangement described the chord represented by a group of strings E, F, F', F², or F³ is changed to a different chord when swinging the corresponding arm or handle L² into a vertical position, so that the range of the instrument is greatly increased, in addition to the change of pitch of all the strings in a group, by means of the movable auxiliary

bridges I and K. The usual fret-board N extends from the bearing H' a suitable distance under the group of melody-strings E, as indicated in Fig. 1.

5 Having thus fully described my invention, I claim as new and desire to secure by Letters Patent—

1. A stringed musical instrument, comprising a body having a sounding - board, fixed 10 bridges, one at each end of the sounding-board, strings arranged in groups and extending over the bridges, a rocking bridge for each group of strings arranged adjacent to one of the fixed bridges and serving to increase 15 the pitch of all the strings of the group, and a rocking bridge for each group of strings arranged adjacent to the other fixed bridge and serving to decrease the pitch of some of the strings of the group, substantially as de- 20 scribed.

2. A stringed musical instrument, comprising a body having a sounding - board, fixed bridges, groups of strings extending over the bridges, three rocking bridges for each group 25 of strings, two of the bridges being arranged adjacent to one another and to one of the fixed bridges, and each serving to increase the pitch of all the strings of the group, the other rock- 30 ing bridge being adjacent to the other fixed bridge and serving to decrease the pitch of some of the strings of the group and thereby change the chord represented by the said group of strings, substantially as described.

3. A stringed musical instrument, comprising a body having a sounding - board, fixed 35 bridges, groups of melody and accompaniment strings extending over the said bridges, two transverse bearings adjacent to one bridge, a third bearing adjacent to the other bridge, and a series of movable bridges, one 40

for each group of strings, mounted to rock in each of the bearings, each of the movable bridges at one end serving to change the pitch of all the strings in the group, and the movable bridges at the other end serving to de- 45 crease the pitch of some of the strings of the group and thereby change the chord represented by said group, substantially as herein shown and described.

4. In a stringed musical instrument, the 50 combination with the sounding-board, and a transverse bearing extending across the same and formed with a semicircular groove in its top, of a plurality of movable bridges arranged end to end in the groove of the bearing and 55 mounted to turn therein, each bridge consisting of a notched bar provided with a handle at one end, substantially as described.

5. In a stringed musical instrument, the 60 combination with a sounding-board, of a trans- verse bearing extending across the same and formed with a semicircular groove in its top, a plurality of bridges in the groove of the bearing and each consisting of a notched bar provided with a handle at one end, and springs 65 extending across the ends of the bridges and holding them in the groove of the bearing, substantially as described.

6. In a musical instrument, a bearing hav- 70 ing a semicircular groove in its top, and a bridge formed of a round bar having its middle portion cut away, and provided with a handle at one end, and springs engaging the ends of the bridge to hold it in the groove of the bearing, substantially as described.
